Primary Examiner — Jack Reickel*Assistant Examiner* — Michael A Kervin(74) *Attorney, Agent, or Firm* — Adrienne Love(57) **CLAIM**

The ornamental design for a sliding door bracket, as shown and described.

DESCRIPTION

FIG. 1 is a front, right-side, top perspective view of a sliding door bracket, showing the new design;

FIG. 2 is a front elevational view thereof;

FIG. 3 is a rear elevational view thereof;

FIG. 4 is a right-side elevational view thereof, the left-side elevational view thereof (not provided) being a mirror image of the right-side elevational view;

FIG. 5 is a top plan view thereof;

FIG. 6 is a bottom plan view thereof; and,

FIG. 7 is a rear, left-side, bottom perspective view thereof. The broken lines depict parts of the sliding door bracket that form no part of the claimed design. The dot-dash chain lines depict boundaries of the claimed subject matter and form no part of the claimed design.

1 Claim, 5 Drawing Sheets(56)
